UNITED STATES PATENT OFFICE

GEORGE SPATTA, OF BUCHANAN, MICHIGAN, ASSIGNOR TO CLARK EQUIPMENT COMPANY, OF BUCHANAN, MICHIGAN, A CORPORATION OF MICHIGAN

METHOD OF MAKING WHEELS

Original application filed May 28, 1928, Serial No. 280,979. Divided and this application filed April 15, 1929. Serial No. 355,070.

This application is a division of my pending application Serial No. 280,979, filed May 28, 1928.

The present invention relates to the method 5 of making metal wheels, particularly of the type employing a sheet metal spider. The particular feature to which the present invention is directed is the manner of uniting the rim and spokes of a wheel of the type 10 closed in my copending application, Serial No. 246,926, filed January 16, 1928.

The spider of the wheel is preferably made of two sheet metal stampings drawn and formed to proper shape, united at their central parts to form a hub and provided with lock seams along their outer margins extending along the sides of the spokes and along the web joining the spokes. Relatively thin sheet metal as of the order of fifty thousandths of an inch in thickness is employed 20 in the preferred embodiment of the invention, and it will be appreciated at once that joining the ends of the spokes to the metal of the rim, which rim is of the order of one hundred twenty five thousandths of an inch 25 in thickness, presents a problem of considerable difficulty to secure the full strength of the parts.

One difficulty is the relatively small 30 strength of the sheet metal to sustain a load in compression because of lack of rigidity.

While the spokes are preferably tubular or cylindrical in contour and present a very considerable strength in bending if properly 35 supported, the spokes must be inserted within the rim in such a manner as to have a close fit and suitable bearing to develop the full strength of the sheet metal spider.

According to the present invention I employ 40 an internal reinforcing member in the end of the spoke, preferably in the form of a short cylinder, the inner end of which is closed, and I weld the side walls of the end of the spoke to this reinforcing thimble at 45 the lock seam or at other points for the purpose of uniting the thimble with the metal of the end of the spoke and thereafter depress the web of the rim into the thimble. This depressing of the web may be carried 50 to the point of puncturing the web of the

rim and expansion of the downturned metal of the flange of the web within the thimble or it need not be carried that far. As an alternative form of my invention the metal of the web may be punched down and expanded into the open end of the sheet metal spoke to form an internal flange in the end of the spoke. This flange may then be welded to the side walls of the spoke and the opening may be closed in any suitable manner as by a sheet metal stopper or plug. The plug 55 might be of solid metal. It may be welded to the rim as by spot welding.

The internal reinforcing thimble provides the necessary hoop strength to prevent splitting or bursting of the end of the spoke and also it gives the thin metal of the end of the spoke additional bearing surface to support a column load. The web of the rim may be 60 spot welded in turn to the end of the lock 65 seams on the spokes to give the spider the ability to support a part of the load at the hub in tension.

Now in order to acquaint those skilled in the art with the manner of constructing and 70 operating a device of my invention I shall describe in connection with the accompanying drawings a specific embodiment of the invention and the method of making the same.

In the drawings:

Fig. 1 is a side view of a wheel constructed in accordance with and embodying my invention.

Fig. 2 is an edge view of the same.

Fig. 3 is a fragmentary sectional detail view illustrating the manner of making the joint between the end of the spoke and the web of the rim.

Fig. 4 is a similar fragmentary sectional view illustrating a modified form of making the joint between the end of the spoke and the web of the rim.

Fig. 5 is a section taken along the line 5, 5 90 of Figure 1 showing a cross section of the spoke.

Fig. 6 is a plan view of the spider pressed into the rim or felloe with the clamping device in place.

Fig. 7 is an edge view of the clamping device.

Fig. 8 is an edge view of a modified form of wheel employing a drop center rim.

Fig. 9 is a cross sectional view taken on the line 9, 9 of Fig. 8.

Fig. 10 is a fragmentary sectional view through the end of a spoke and the adjacent part of the rim taken on the line 10, 10 of Fig. 8; and

Fig. 11 is a similar fragmentary sectional view of a modified form of joint between the rim and the end of a spoke.

While in the drawings I show a wheel of the type employing a demountable rim and another wheel showing a drop center rim for receiving a tire directly, I do not wish to be limited to either specific form, although it is desirable to close any perforations in the web 10 of the rim where the tire bears directly upon the rim, as in the case of the drop center rim.

The wheel shown in Figs. 1, 2 and 3 comprises a felloe 1 formed of an endless circular outwardly facing channel section having a wider flange 2, a narrower flange 3 and joining web 4. This form of rim may be bought on the open market and secured with holes 5 formed therein for receiving the clamping bolts for holding a demountable rim, as is well understood by those skilled in the art. The rim may also have holes 6 punched therein for receiving the ends of suitable wedge members employed in conjunction with bolts for holding the demountable rim in place.

The spider 7 is made of sheet metal. Two complementary stampings blanked out and drawn in dies, as disclosed in my copending application, Serial No. 280,981, filed May 28, 1928, are first formed and then joined together by tubular shouldered rivets such as the rivet 8 shown in Fig. 9 and then joined together at their edges by lock seams such as the lock seams 9 shown in Figures 5 and 9 employing suitable channel strips 10 to form the lock seams.

The stampings employ each a central hub disc 11 joined to the web 12 by a shoulder 13, the size of this shoulder varying for hubs of different depth or thickness. A central opening 19 is formed through the hub and the opening is defined by inturned flanges 14, 14, formed on each of the plates 11. The plates 11, 11 are connected by the shouldered hollow rivets 8 having the heads 15, 15 beaded over and lying in the depressions in the plates 11 so that the heads 15, 15 do not project beyond the outer surface of the plates 11. The stampings are provided with outwardly extending or curled flanges 17, 17 as may be seen in Figures 5 and 9, these curled flanges extending on the sides of the spokes 18, 18, and the parts of the web 12 between spokes, and the U-shaped channel strips 10, 10 are closed over the flanges 17, 17 and swaged

down to form lock seams, which lock seams 9 terminate flush with the end of the spoke on each side.

After the spider is completed it is gripped in a two part clamping ring, the parts being applied on opposite sides and gripping the ends of the spokes, and then the spider with the clamping ring thereupon is pressed laterally into the rim 1 to insert the spider in the rim.

In order to strengthen the ends of the spokes for this pressing operation and for the subsequent operations, there are introduced into the ends of the spokes before the clamping ring is applied thimbles 20, 20 as shown in Fig. 3, these thimbles having cylindrical side walls and the closed end wall 21. The thimbles are welded to the side walls of the spoke ends, preferably as indicated in Figs. 3 and 4, by a spot weld at 22 extending through the lock seams 9.

If desired, the welding of the thimbles 20 to the ends of the spokes may be performed by spot welding on each side of the lock seams 9, 9. However, it is advantageous to weld through the lock seams in order to weld the flanges and the channel strip 10 together at this point.

The clamping ring 33 is a split clamp made up of similar halves 34 and 34' having radial holes or slots 35 fitting closely the ends of the spokes. The two halves of the ring are held together by the clamping screws 37 so as to hold the spider securely. The clamping members 34 and 34' are chamfered off at 38 and 38' to provide conical surfaces and have cylindrical parts 39 and 39' of a width slightly greater than the diameter of the spokes, so as to support firmly each of the spokes, particularly around the outer edges of the spokes upon closing of the clamp. The diameter of the clamping rings at 39 is substantially equal to or slightly less than the diameter of the spider.

After the spider with the thimbles in the ends of the spokes has been inserted in the rim 1, the wheel is placed in a press, the clamping ring being suitably supported by the bed of the press, and a punch is forced through the web 4 of the channel to pierce the web and turn the flanges 23 downwardly into the interior of the thimbles 20.

The punching and expanding of the flange 23 is done while the clamp supports the web 4 and the end of the spoke 18, the clamping ring taking the endwise thrust and also sustaining the radial pressure about the flange 23 in the thimble 20. The flange 23 is thus pressed or swaged firmly into engagement with the cylindrical wall of the thimble 20 and thereafter the web 4 is welded to the ends of the lock seams 9 at 25. The spot weld at 25 may be omitted if desired, as shown in the modification of Fig. 4. A weld may be formed through the down turned flanges 23

and the wall of the thimble 20 and the outside wall of the spoke 18 either through the lock seam 9 or through only the single thickness of sheet metal on each side of the seam 9.

6 The closed end 21 of the thimble 20 prevents the entrance of moisture or other foreign material into the interior of the hollow spider, the spider being closed at all other points. The openings 24 produced by drawing down on the flanges 23 are not objectionable in the form shown in Figures 1 and 2 since the felloe 1 supports a demountable tire rim.

10 If, however, the construction is to be employed with a drop center rim bearing the tire directly, the opening 24 may be closed by a plug or sheet metal stopper, such as that shown at 27 in Fig. 11.

15 Where a drop center rim such as 30 (see Figs. 8 and 9) is employed, the construction of the spider may be the same as previously described, and the web of the drop center part 31 has the spider forced thereinto to secure a close fit. The web 31 in this case (see Fig. 20) is preferably not punctured but is merely depressed as indicated at 32 into the open end of the spoke and the open end of the thimble 20. The thimble 20, prior to the introduction of the spider into the rim, is 25 welded to the lock seam 9 by welds indicated at 22, 22, and after the spider has been forced into the rim and a depression 32 formed in the web 31 the end of the spoke may be 30 welded to the web 31 by means of the spot welds at 25, 25 as shown in Fig. 10.

35 Where the thimble 20 is employed in the end of the spoke the spider may be forced into the rim under considerable pressure, that is, with a relatively close press fit so as to put 40 the rim under tension and the spider under considerable compression. Where welds are formed between the outer ends of the spoke and the web of the rim, as shown in Figs. 3, 10 and 11, the load at the hub may 45 be carried partly in tension as well as in compression of the spokes.

40 In Fig. 11, I have shown a modified form of union between the ends of the spokes and the web 31 of the drop center rim 30. This 50 form of union may be employed in connection with the felloe 1 shown in Figs. 1 and 2 if desired. In this case the thimble 20 is omitted, the spokes being gripped in the clamping ring and pressed into the rim 30, 55 and while thus supported in the clamping ring the web 31 is punctured and the flange 32 pressed or swaged into contact with the inside wall of the spoke 18, the same being supported by the clamping ring. Thereafter 60 the end of the spoke is welded through the lock seam 9 to the depending flange 32 by a weld indicated at 43 to unite firmly the end of the spoke and the flange 32 punched out of the rim 30. The weld 43, instead of being 65 formed at and through the lock seam, may

be formed on either side of the same through a single thickness of sheet metal of which the main part of the shaft of the spoke is formed.

70 Thereafter the end of the lock seam 9 may be spot welded as indicated at 25 to the web of the rim. The opening 44 produced by punching down the flange 32 may be closed as by the sheet metal plug 27 or by any other suitable plug which may in turn be welded 75 to the web of the rim or may be held with a friction fit in the opening 44.

80 I do not intend to be limited to the details shown and described nor to the exact sequence of operations herein referred to, as it will be obvious to those skilled in the art 85 that numerous deviations will be permissible within the spirit and scope of the appended claims.

85 I claim:

1. The method of making a wheel which comprises forming an endless rim of outwardly facing channel section forming co-operating spider stampings of larger external diameter than the internal diameter of the 90 rim, uniting the meeting edges of the spider with lock seams and at the hub portion with rivets to form a spider having a hub and radiating sheet metal spokes, forming closed end cylindrical thimbles, forcing the thimbles 95 into the ends of the spokes with their open ends substantially flush with the ends of the spokes, welding the thimbles to the ends of the spokes, tensioning the rim on to the spider by pressing the spider into the rim, piercing 100 the web of the rim to produce flanges extending into the ends of the thimbles thereby further tensioning the rim on the spider, and welding the ends of the lock seams to the web 105 of the rim.

2. The method of making a wheel which comprises forming an endless rim of outwardly facing channel section, forming a spider of two sheet metal stampings, uniting the stampings at their edges by lock seams terminating at the edge of the spider spokes, forcing the completed spider laterally into the rim, piercing the web of the rim to produce flanges extending into the ends of the spokes, welding the flanges to the lock seams, 110 welding the ends of the spokes to the rim and plugging the openings in the web.

3. The method of making a wheel which comprises forming an endless rim of outwardly facing channel section forming co-operating spider stampings, uniting the meeting edges of the spider with lock seams to form a spider having a hub and radiating sheet metal spokes, securing the hub portions together by rivets, forming closed end cylindrical thimbles, forcing the thimbles into the ends of the spokes, welding the thimbles to the ends of the spokes, tensioning the rim on the completed spider by pressing the spider 120 into the rim, and further tensioning the rim 125

130

on the spider by piercing the web of the rim to produce flanges extending into the ends of the thimbles.

4. The method of making a wheel which comprises forming two complementary spiders having semitubular spokes united by lock seams along the meeting edges of the spokes and hub sections of the spider, inserting strengthening members into the ends of the spokes, mounting the spokes in a clamping ring the end of which is substantially flush with the end of the spokes, forcing the spider with the clamping ring thereon into an endless rim of slightly smaller internal diameter than the external diameter of the spider, whereby the ring prevents distortion of the spokes during the pressing operation, piercing the web of the rim to produce flanges extending into the ends of the spokes, welding the spokes to the web of the rim and removing the clamping ring.

5. The method of making a wheel which comprises forming two complementary spiders having semitubular spokes united by lock seams along the meeting edges of the spokes and hub sections of the spider, inserting strengthening members into the ends of the spokes, mounting the spokes in a clamping ring the end of which is substantially flush with the end of the spokes, forcing the spider with the clamping ring thereon into an endless rim of slightly smaller internal diameter than the external diameter of the spider, whereby the ring prevents distortion of the spokes during the pressing operation, piercing the web of the rim to produce flanges extending into the ends of the spokes, welding the spokes, the strengthening members and the rim together, and removing the clamping ring.

In witness whereof I hereunto subscribe my name this 9th day of April, 1929.
GEORGE SPATTA.
